(57) **CLAIM**

I claim the ornamental design for a bird feeder hood, as shown and described.

DESCRIPTION

FIG. 1 is a perspective view of a bird feeder hood;

FIG. 2 is a first side view thereof;

FIG. 3 is a second side view thereof;

FIG. 4 is a third side view thereof;

FIG. 5 is a fourth side view thereof;

FIG. 6 is a top plan view thereof; and,

FIG. 7 is a bottom view thereof.
